cago, Ill., a corporation of Delaware

Application June 4, 1945, Serial No. 597,461

33 Claims. (Cl. 179—27)

1

The present invention relates in general to telephone systems, and more particularly to improved switching apparatus for distributing calls to a plurality of operator positions in a cordless switchboard.

A cordless switchboard conventionally comprises a plurality of lines, which may be divided into a number of classes each of which may include several groups of lines, a number of operator positions each having a plurality of links having access to said lines, and a common call distributor operative in response to a call over any one of said lines to cause an idle one of said links to seize the calling line.

In the past various means have been employed to distribute the calls with the object of equalizing the waiting time between the reception and answering of each call. For example, it has been proposed that a distributor be used which would mark a batch of calling ones of the lines to idle ones of the links, and which would prevent marking of lines over which calls are subsequently received until all calling lines in the marked batch had been seized by the idle links. It has also been proposed that a distributor be used which would mark several groups of calling ones of the lines to idle ones of the links causing them to seize said calling lines group by group, and which would prevent further marking of calling lines in a group, after all initial and subsequently received calls over lines in said one group had been answered, until calling lines in all other groups had been seized. When the lines are divided into several classes and certain positions are allocated to answer a particular class exclusively, the first method has the disadvantage of not allocating any calls to said certain positions, after the calls of said particular class have been answered, until the calls of all other classes in the same batch have been answered by the other positions. This objection is overcome in the second method by using separate distributors for each class of service. However, as this second method has been practiced in the past it is subject to another objection not present in the first method; namely, that as long as calls continue to be received in any one group, calls in other groups may be delayed. In order to overcome such a delay it is necessary to provide a graded multiple between the positions so that a different group is given preference in each position.

It is accordingly an object of the present invention to provide an improved call distributing arrangement which will mark batches of calling lines in each of a number of classes independ-

ently, which will cause idle links in positions allocated to any one or more classes to seize the marked calling ones of said lines in the corresponding classes, and which will mark a new batch of calling lines in each class when the previously marked batch in that class has been exhausted.

A further object of the invention is to provide a call distributing arrangement as stated in the preceding object wherein certain positions are allocated to answer calls in two or more classes, in which means individual to each position are provided to prevent further answering of calls in one of said classes by said certain positions, when 10 all calls of that one class included in a batch have been exhausted, until the calls of each other class included in a batch have been exhausted.

A still further object of the invention is to provide a call distributing arrangement as stated in the preceding objects wherein other positions are allocated to receive only one of the classes of calls allocated to said certain positions, in which said means individual to each position will permit 20 a new batch of calls to be answered by said other positions, when the previous batch of calls of the class allocated thereto has been exhausted, regardless of whether or not batches of calls in the other classes have been exhausted by said certain positions.

Another object of the invention is to provide 25 means causing simultaneous calls in different classes to be given a desired order of preference at a position which is different than the order in which corresponding marking circuits are 30 scanned by the links in searching for a calling line.

Still another object is to provide means for 35 removing a marking corresponding to a group of lines in case a link attempts to find a calling line in said group but fails to do so, thereby preventing a false marking of any line in the group from blocking other groups of lines.

Another object is to provide means for marking 40 new batches of calling lines in all classes in case a link attempts to find a calling line in the last choice group of the last choice class but fails to do so, thereby preventing a false group marking from blocking all calls.

A further object is to provide an improved link 45 and control circuit therefor wherein certain conductors are marked by the control circuit to identify a sub-group of calling lines to a link when said link is searching for a calling line in said sub-group, and wherein said certain conductors are marked by the link when a line has 50 55

been seized in the corresponding sub-group to identify the sub-group to an operator at the position associated with the link.

A still further object is to provide an improved link and control circuit therefor wherein the character of an acceptance tone transmitted to the operator in response to the acceptance of a call by an associated link identifies the class of call being answered.

Other objects of the invention will appear upon a further perusal of the specification taken in conjunction with the accompanying drawings, in which:

Fig. 1 is a schematic trunking diagram showing the general arrangement of a telephone system embodying the present invention;

Figs. 2, 3 and 4 show conventional trunk circuits adapted for use with a call distributor incorporating the invention;

Fig. 5 is a schematic diagram of an improved link circuit;

Figs. 6 and 7 taken together comprise a schematic diagram of an operator's position equipment and novel link control circuits associated therewith;

Figs. 8 and 9 taken together comprise a schematic diagram of a novel call distributor constructed in accordance with the invention;

Fig. 10 shows a supervisor's equipment;

Fig. 11 shows conventional distributors for routing calls to idle operator's positions; and

Fig. 12 illustrates the mode of combining Figs. 2 to 11, inclusive, in order to form a unified system.

A brief description of the invention will first be given and will be followed by a detailed description of the illustrated embodiment thereof. As previously noted, a system embodying the invention comprises a plurality of lines or trunks of several different classes, a plurality of operator's positions each having a number of links having access to the lines or trunks, and a common call distributor for causing idle links to seize calling ones of the lines. As in prior circuits where calling lines are marked batch by batch, a pair of conductors extend from the trunk circuits to the common call distributor and each trunk is provided with a relay whose operating circuit includes a normally open point individual to the trunk, one of said conductors, and a normally closed point in the call distributor common to a number of such relays. When a call is received over a trunk, the normally open point in the operating circuit of the relay associated therewith is closed, thereby operating the relay to mark the trunk and to extend a start signal to the call distributor over the remaining conductor of said pair. The call distributor opens said common point in response to the start signal to thereby prevent the operation of other such relays in response to the reception of calls over other trunks, and directs an idle link to find the marked trunk. Upon seizure of the marked trunk by a link the start signal is removed, thereby causing the call distributor to reclose said common point to permit operation of the relays associated with trunks over which calls have subsequently been received. In accordance with the present invention, a pair of conductors is provided for each class of trunks, a normally closed point in the call distributor common to all of the trunk marking relays in each class being provided and being connected in series therewith over one conductor of the corresponding pair. In response to a start signal over the other conductor

of any pair, the call distributor opens the common point in the operating circuits of the corresponding class of trunk marking relays, thus preventing subsequent marking of other trunks in that class independently of the remaining classes. Thus independent batches of calling lines are marked in each class. Now if all operator's positions are to answer all classes of calls and each position gives preference to the different classes in the same order, it is apparent that no calls in the last choice classes would be answered if calls continued to be received in the first choice classes since each is marked in independent batches. In order to prevent a call included in a second batch of a first choice class from being answered prior to a call included in a first batch of a last choice class, at a position allocated to answer both classes, a further call distributing arrangement individual to each position is provided. This individual distributing arrangement prevents further answering of calls in a first choice class at the associated position, once a batch thereof has been exhausted, until all marked calls in corresponding batches of later choice classes have been answered. However, new batches of calls may be answered at other positions allocated to answer any one choice class exclusively. For example, assume that there are three classes of trunks A, B and C, and that there are four positions, one of which answers calls in any of the three classes and the other three of which each answer a particular class exclusively. The trunks will be marked in separate and independent batches at varying intervals of time depending upon the calling rate and answering time prevailing for each class. There is thus no true correspondence between batches of marked trunks in different classes. Each of the positions answering a particular class will act independently of the other two. However, the one position that is answering calls in all three classes is automatically caused to assist any one of the other three positions which is overloaded, or to assist all three other positions equally, by the distributing arrangement individual to said one position. Assuming that the other three positions are equally loaded, at a given instant when the one position starts to answer calls in class A there will be a batch of marked lines in each of the three classes A, B and C. These three batches are referred to as corresponding batches, it being understood that when one of these batches is exhausted and a new batch is marked in that class that this new batch does not correspond to the other two batches even though they overlap in time. Said one position will now answer calls in all three classes, thereby assisting the other three operators, until a batch of one class has been exhausted. If the batch of class A calls is the first to be exhausted a new batch thereof will be marked and answered by the other operator allocated thereto exclusively, but said one operator will be prevented from answering any more class A call, class B and C calls being answered thereby instead thus further assisting the other operators allocated exclusively thereto. When one of the corresponding batches of these last two classes has been exhausted, say class C for example, a new batch thereof will be marked and answered by the other operator allocated exclusively thereto, said one operator being prevented from answering any more class C calls until the remaining batch of class B calls is exhausted. Thus the greatest assistance is given to the heaviest loaded one of the other

operators by said one operator. When the remaining batch of class B calls has been exhausted, three new corresponding batches of calls are shared by said one operator with the other three operators. The individual distributing arrangement is further arranged so as to permit ready disablement thereof for any one or more of the several classes so as to provide preference to particular classes at certain operator's positions. The manner in which these results are accomplished will best be understood from the following detailed description.

Preparing an operator's position to receive calls

When the operator's position shown in Figs. 6 and 7 is occupied the plug 711 of the operator's headset 710 is inserted into jack 712 thereby completing a circuit to relay 700 in series with the transmitter of the headset. Relay 700 operates, connects lamps AN, BN, and CN to leads AL, BL, and CL, respectively, at contacts 702, 703, and 704 in series with contacts on the class of service keys 730, 740 and 750 corresponding to each lamp. The letters A, B, and C represent the three classes of service into which the various types of calls are subdivided. These letters have been prefixed to the reference characters of all leads and relays associated with a particular class of service to facilitate a clear understanding of the invention. The leads AL, BL, and CL extend through a cable to the call distributor (Fig. 9). Relay 700 also completes a circuit to relay 680 at contacts 705 and prepares circuits to relays AP, BP, and CP from leads APG, BPG, and CPG, respectively, through contacts of the corresponding class of service keys at contacts 706, 707, and 708. The APG, BPG, and CPG leads also extend through a cable to the call distributor (Fig. 9). Relay 680 operates and further prepares the circuits to relays AP, BP, and CP at contacts 681, 682, and 683, respectively. It will be noted that terminals are provided so as to permit ready strapping of any of these latter contacts, of which the first is shown strapped. For the moment this strap will be ignored.

When the operator at the position shown is ready to receive calls she will operate a link key, such as LK1 (Fig. 6), to its locking position (i. e. to the left) thereby completing an operating circuit to the lower winding of relay 560 (Fig. 5) of the corresponding link from ground at contacts 701, through contacts 621 and LK12 to relay 560 over lead OG1. Relay 560 operates and closes a circuit to its upper winding at contacts 569 over lead HG1, through contacts LK11 and relay 620 to ground. Relay 620 operates, opens the operating circuit to relay 560 and closes a circuit to relay 670 at contacts 621. Relay 560 remains operated due to the energization of its upper winding in series with relay 620. It should be understood that a similar key LK2 and corresponding leads OG2 and HG2 are provided for the second link, and so on. Relay 670 operates; removes ground from guard leads AGD1, BGD1, and CGD1 at contacts 671, 672, and 673, respectively; and closes ground from contacts 684, 685, and 686, through contacts 674, 675, and 676 and contacts of the corresponding class of service keys to position distributor start leads ADS, BDS, and CDS, respectively. The distributor start and guard leads for each of the three classes of service extend over a cable to the position distributors (Fig. 11).

Only one position distributor has been shown in detail in Fig. 11 since they are all identical.

Each distributor has a common distributor start lead, such as CDS, extending therefrom to all operator's positions, and a pair of individual guard and start leads, such as CGD1 and CST1, extending to a particular position corresponding to the suffix number. As long as any occupied position allocated to receive class C calls has a link key of an idle link thrown, the CDS lead will be grounded. When this lead is grounded initially, the lower winding of relay 1120 is energized thereover in series with contacts 1111. Relay 1120 operates, closes a holding circuit through its upper winding in series with relay 1110 and contacts 1131 at contacts 1122; connects lead CGD1 to the lower winding of relay 1130 in series with contacts 1151 at contacts 1123; and extends lead CST1 to lead CST at contacts 1125. Relay 1110 operates and opens the operating circuit to relay 1120 at contacts 1111. Since it has been assumed that the position equipment shown in Figs. 6 and 7 represents the first position and is now prepared to receive calls, there will be no ground on the guard lead CGD1 and consequently the lower winding of relay 1130 will not be energized at this time. Each of the other distributors operates in a similar manner to extend leads AST1 and BST1 coming from position 1 (Fig. 7) to the leads AST and BST, respectively, extending from the call distributor (Fig. 9) to the corresponding position distributors.

Answering a class A call

Referring now to Fig. 1, three incoming trunks are shown terminating in a toll selector, a suburban selector, and a toll information trunk circuit. The toll selector is employed by toll operators at a distant office to extend toll calls to local subscribers over a toll switch train which is not shown, or via the repeater and toll selector intercepting trunk circuit shown to an information operator through the cordless switchboard. The suburban selector is employed by subscribers of nearby offices to complete connections to local subscribers over the local switch train, or via the suburban information trunk to an information operator through the switchboard. A similar local information trunk is accessible from the local selector to permit local subscribers to call an information operator through the switchboard. The toll information trunk is employed by toll operators at a manual toll switchboard to call an information operator through the switchboard. Since the switch trains follow conventional practice they have been omitted in the detailed circuit diagrams. The trunk circuits have been shown in detail although they differ from conventional practice only in the adaption thereof to suit the novel call distributor.

The toll selector intercepting trunk circuit shown in Fig. 2 is seized over conductors 281 and 282 when ringing current is transmitted thereover from a preceding repeater under the control of a toll operator. The ringing current flows through condenser 283 and relay 200 in series causing this relay to operate and complete a circuit to relay 230. Relay 230 operates, closes its locking circuit at contacts 232, connects relay 220 to conductor AH at contacts 233, and grounds lead 284 to light a call waiting lamp not shown. For convenience, calls received over the trunk circuits of Figs. 2, 3, and 4 are hereinafter referred to as class A, B, and C calls, respectively. As previously noted, all conductors and relays associ-

ated with a particular class of service have been prefixed with the corresponding letter A, B, or C. Thus the AH lead to which relay 220 has been connected is associated with the class A trunk circuits. If there are no unanswered class A calls this lead will be grounded at contacts AG3 in Fig. 8, but if a batch of class A trunks have previously been marked there will be no ground on lead AH until all of the marked trunks have been seized by idle links. In either case, when ground is present on lead AH relay 220 operates; closes its locking circuit and opens its operating circuit at contacts 224; closes a multiple locking ground to relay 230 at contacts 221; at contacts 222 connects relay 260 to lead 295, which is multiplied to corresponding bank contacts of all links to mark the trunk circuit; and grounds lead AS to extend a start signal to the call distributor (Fig. 8) at its contacts 223. The class A trunks may be divided into a number of groups, each corresponding to a particular level of bank contacts of the links. In the present instance it is assumed that the class A trunks appear on two different levels of the links and therefor two AS leads are provided. Lead AS1 is connected to relay A1 and is multiplied to all of the class A trunks in one group, while lead AS2 is connected to a similar relay A2 (not shown) and is multiplied to all of the class A trunks in the second group. Assuming that lead AS1 was grounded by relay 220, relay A1 operates in series with contacts AG1, closes its holding circuit at contacts A11, grounds lead VAI at contacts A13, and closes a circuit to relay AD of Fig. 9 at contacts A14. Relay AD operates, grounds lead AL at contacts AD1 to light the corresponding class of service lamps, such as AN (Fig. 7), at all occupied operator's positions allocated to receive class A calls and in the supervisor's circuit (Fig. 10), opens the circuit to normally operated relay AG and grounds lead AST at contacts AD3, and grounds lead APG at contacts AD2. Relay AG releases after a brief delay and opens the operating circuits to relays A1 and A2 at contacts AG1 and AG2, respectively; and removes ground from the AH lead to prevent marking of class A trunks over which calls may subsequently be received. Relay A1 remains operated due to the shunting of contacts AG1 by contacts A11.

The ground placed on lead APG by relay AD completes a previously traced circuit to relay AP (Fig. 6), and to corresponding relays of other occupied positions allocated to receive class A calls. Relay AP operates, opens the circuit to relay 680 at contacts AP1, shunts contacts 681 at contacts AP2, closes a multiple ground to the ADS lead at contacts AP4, and closes a circuit to relay AR from ground at contacts AD3 (Fig. 9), over lead AST, through contacts such as 1125 of the "A" position distributor (Fig. 11), over lead AST1, through contacts 691 (Fig. 6), contacts AP5 and 677, through relay AR and contacts AR3, CR5, BR10, and AR6 to negative battery. Relay AR operates, closes its locking circuit through its preliminary make contacts AR7, opens points in its operating circuit at contacts AR6 and AR8, closes a circuit to relay 660 at contacts AR1, transfers lead AE from the identity lamp AEL to ground at contacts AR3, and connects leads VAI and VA2 to leads L1 and L2, respectively, at contacts AR5 and AR4, thereby marking level 1 to the link since the VAI lead was grounded by relay A1 in the call distributor (Fig. 8). The L1 to L2 leads extend over a cable to a set of vertical marking contacts of the link (Fig. 5).

and are multiplied to all links associated with the first position.

Relay 680 restores after a brief delay, opens the operating circuit to relay AP at contacts 681, grounds the BGD1 and CGD1 leads at contacts 684 through contacts BP3 and CP3, respectively, and removes ground from the BDS and CDS leads at contacts 685 and 686, respectively. If other positions are occupied the BDS and CDS leads will be grounded thereby and the ground placed on the BGD1 and CGD1 leads will cause the corresponding position distributors to advance to the next idle position. The ground on CGD1 energizes the lower winding of relay 1130 (Fig. 11) through contacts 1123 and 1151. Relay 1130 operates, closes a locking circuit to its upper winding at contacts 1132 through contacts 1141 and relay 1110 to ground over the CDS lead, opens the locking circuit to relay 1120 at contacts 1131, and extends the CST lead to lead CST2 at contacts 1135. Relay 1120 restores, opens the operating circuit to relay 1130 at contacts 1123, connects the CGD2 lead to the lower winding of relay 1140 at contacts 1124 through contacts 1134, and disconnects lead CST from lead CST1 at contacts 1125. If the second position is busy the CGD2 lead will be grounded and the chain will continue to advance until an idle position is reached. If all positions are busy there will be no ground on the CDS lead and all relays will then restore to normal. The "B" position distributor operates in the same manner to extend the BST lead to an idle position.

Relay 660 operates in response to the operation of relay AR and closes a circuit from ground through contacts 661, through the low resistance upper winding of relay 650, through contacts 611, over lead ST to the link (Fig. 5), thence through contacts 567, SR11, and 533 to the high resistance lower winding of relay 540. Relay 650 does not operate over the above traced circuit due to the high resistance of the lower winding of relay 540. Relay 540 operates and closes a circuit from ground through contacts 511, 527, 543, 571, and 583 to the vertical magnet VTM. VTM operates to advance the link wipers W1 to W5 to the first level, and closes a circuit to relay 570 at contacts VTM1. The advancement of wiper W5 to the first level marking contact completes a circuit from ground on lead L1 over wiper W5, through the upper winding of relay 580, and through contacts 584 and 537 to relay 570 in multiple with the circuit completed thereto by contacts VTM1. Relay 570 operates and opens the circuit to VTM at contacts 571. When VTM restores it removes a short circuit from the upper winding of relay 580 thereby energizing this winding in series with relay 570 causing relay 580 to operate its preliminary make contacts 585 which complete a circuit to its lower winding. Relay 580 then operates completely, connects the low resistance upper winding of relay 540 in parallel with its lower winding at contacts 581, grounds lead LB1 at contacts 582 to light the first link busy lamp LB1L (Fig. 6), opens a second point in the operating circuit to VTM and prepares a circuit to the rotary magnet ROM at contacts 583, and opens the circuit to relay 570 through the upper winding of relay 580 at contacts 584. Relay 570 restores and closes the circuit to ROM at contacts 571. ROM operates to rotate the wipers W1 to W4 to the first set of bank contacts in the first level and to disengage wiper W5 from the set of vertical marking contacts, and closes a circuit to relay 570 at contacts ROM1. Relay 570 operates

and opens the circuit to ROM at contacts 571. ROM restores and opens the circuit to relay 570 at contacts ROM1. Relay 570 restores and recloses the circuit to ROM. ROM reoperates, advances wipers W1 to W4 to the second set of contacts in the first level, and recloses the circuit to relay 570. This cycle of operations continues until wiper W3 engages the contact connected to lead 285 which has been marked by the connection of negative battery thereto through relay 260 (Fig. 2). When this contact is reached a circuit is completed from negative battery over lead 285, through wiper W3, contacts 523, relay 510, contacts 532, wiper W4, and over an E lead common to all of the link bank contacts associated with class A trunks (i. e. lead AE) to ground through contacts AR3 (Fig. 6). Relays 510 and 260 operate over the above traced circuit and relay 510 opens the circuit to ROM to prevent further rotary stepping and closes a circuit to relay 520 at contacts 511. Relay 260 operates, closes a circuit to relay 210 at contacts 262, closes its locking circuit at contacts 263, and opens the circuit to relay 220 at contacts 264. Relay 210 operates, opens the circuit to relay 200 and connects resistance ground through windings of impedance coil 240 to conductors 281 and 282 to operate a ring trip relay in the preceding repeater at contacts 211 and 212, and removes ground from start lead AS at contacts 214. Returning now to Fig. 5, relay 520 operates in response to the operation of relay 510; transfers wiper W3 from ground through relay 510 to ground through relay 500 at contacts 523, extends leads 286 and 287 through wipers W1 and W2 to leads R1 and R2 through contacts 563 and 564, condensers 503 and 504, and contacts 591 and 592, at contacts 521 and 522, respectively, connects ground to wiper W4 through contacts 532, 524, and 541, opens its operating circuit and closes its locking circuit to contacts 582 at contacts 525, and closes a circuit from ground through contacts 526, 568, over lead RS to relay 610 (Fig. 6). Relay 500 operates in series with relay 260 (Fig. 2). Relay 510 restores.

It will be recalled that when relay 580 operated it connected the low resistance upper winding of relay 540 in parallel with its lower winding, thus lowering the resistance in series with the upper winding of relay 650. Relay 650 operates, transfers the end terminals of the secondary winding of the operator's induction coil IND from leads R1 and R2 to ground through condenser 622, and through contacts AR2 and condenser 623 to a source of tone current not shown at contacts 652 and 651, respectively, and closes a circuit to its lower winding through resistance 624 in multiple with relay 640 at contacts 653. Relay 640 operates after a brief delay, closes a multiple circuit to itself and the lower winding of relay 650 from ground through contacts 661 at contacts 642, and closes a circuit to relay 630 at contacts 643. Relay 630 operates after a brief delay and short-circuits the upper and lower windings of relay 650 at contacts 633 and 634, respectively. Relay 650 restores and reconnects the secondary winding of IND to leads R1 and R2 at contacts 651 and 652. Relays 630 and 640 remain locked to ground from contacts 661. During the time that relay 650 was operated, a continuous tone is transmitted from the tone source to the secondary winding of IND. The center portion of this winding is connected to the receiver of the operator's headset 770 causing a single long audible tone to be given to the operator to inform her

of the acceptance of a class A call by an idle link associated with her position. In the event that a class B or C call was being accepted, relays BR or CR would have been operated in place of relay 5 AR as will presently be described. In this event the tone current would have been transmitted through condenser 623, contacts 641 and contacts 651 after relay 650 operated until relay 640 operated to interrupt the tone current path at contacts 641. The subsequent operation of relay 630 would then close a second tone path through contacts 641 at contacts 632. The subsequent release of relay 650, after a brief delay caused by the slugging effect of its short-circuited windings, would then interrupt the tone path a second time at contacts 651. Thus when a class B or C call is accepted the operator receives two short audible tone signals.

Relay 610 operates from the ground placed on lead RS by relay 520 (Fig. 5), connects direct ground to lead ST at contacts 611, and opens the circuit to relay 670 at contacts 612. Relay 670 restores, grounds the AGD1 lead at contacts 671 to cause the A position distributor to advance to the next idle position in the manner previously described, removes ground from the ADS lead at contacts 674 to restore the A position distributor to normal in case there are no other idle positions, and opens the circuit to relay AR at contacts 677. Relay AR restores and transfers lead AE from ground to lamp AEL which lights due to the ground placed on lead AE over wiper W3 of the link (Fig. 5) thereby indicating to the operator that a class A trunk has been seized. Relay AR in restoring also opens the circuit to relay 660 which restores and opens multiple holding circuits to relays 630 and 640 at contacts 661 thus permitting these relays to restore.

When the trunk circuit of Fig. 2 was seized, relay 210 operated and removed ground from the AS lead at contacts 214 thus opening the circuit to relay A1 (Fig. 8). Relay A1 restores and opens the circuit to relay AD (Fig. 9) at contacts A14. Relay AD restores, removes ground from lead AL at contacts AD1 to extinguish all class A call waiting lamps, such as AN (Fig. 7), removes ground from the APG lead at contacts AD2 to release all operated position grouping relays, such as relay AP (Fig. 7), and removes ground from the AST lead and closes a circuit to relay AG (Fig. 8) at contacts AD3. Relay AG operates and grounds the AH lead.

When the trunk circuit of Fig. 2 was seized the circuit to relay 220 was opened at contacts 264. After a brief delay relay 220 restores and opens the locking circuit to relay 230 at contacts 221. Relay 230 restores, connects relay 270 across leads 286 and 287 at contacts 231, and opens the circuit to the call waiting lamp not shown at contacts 234. All of the common equipment has now been freed and a talking circuit is established between the distant toll operator and the information operator over conductors 281 and 282 through condensers 283 and 288, over leads 286 and 287, through wipers W1 and W2, contacts 521 and 522, 591 and 592, condensers 503 and 504, contacts 563 and 564, over leads R1 and R2, and through contacts 602 and 603, 635, 651 and 652 to the secondary winding of the induction coil IND. The center portion of this secondary winding is wound with resistance wire to balance the impedance of the line connected across the whole secondary winding, this being a well known antisidetone circuit. Speech currents received over the line are therefore reproduced by the re-

ceiver of the operator's headset 770, whereas speech currents produced by the transmitter of the operator's headset flowing through the primary winding of IND induce corresponding voltages in the several sections of the secondary winding which are connected so as to produce speech currents in the line but not in the operator's receiver. When operating practice or circuit requirements necessitate acknowledgement of the answering of a call the operator may operate the flash key 780 (Fig. 7) momentarily, thereby grounding the FL lead which extends over a cable to the link (Fig. 5) thence through contacts 544 to relay 590 which operates and transfers wipers W1 and W2 to negative battery and ground, respectively, at contacts 591 and 592. A circuit is thus completed to relay 270 (Fig. 2) which operates and closes a circuit to relay 250 at contacts 272. Relay 250 operates, closes its locking circuit to ground through contacts 262 at contacts 253, and transfers leads 281 and 282 from resistance ground to a loop circuit through contacts 271 at contacts 251 and 252. The low resistance loop circuit operates a back-bridge relay in the preceding toll selector which reverses battery to the distant office. When the flash key 780 is released relay 590 restores and releases relay 270 which restores and opens the loop circuit to leads 281 and 282 at contacts 271, and opens the operating circuit to relay 250 at contacts 272. Relay 250 remains locked to contacts 262. Opening the loop again causes battery to be reversed to the distant office in the preceding toll selector.

Releasing the connection

After the distant operator has obtained the desired information from the information operator, the latter momentarily operates a common release key 710 (Fig. 7) thereby grounding the RSC lead which extends over a cable to the link (Fig. 5) thence through contacts 561' to relay 530. Relay 530 operates, opens the circuit to relay 540 at contacts 533, and opens the locking circuit for relay 580 and closes a locking circuit to itself through contacts of the vertical off-normal springs VON at contacts 536. Relay 540 restores. Relay 500 restores and at contacts 582, opens the locking circuit to relay 520, opens the circuit to link busy lamp LB1L over lead LB1, and closes a circuit to the release magnet RLM through contacts 534 and contacts of VON. Relay 520 restores and opens the circuits to wipers W1, W2 and W3 at contacts 521, 522, and 523, thus opening the circuit to relay 500 in series with relay 260 (Fig. 2) over lead 285. Relay 500 restores. The release magnet RLM operates to release the link switching mechanism which restores and opens the vertical off-normal springs VON, thereby opening the locking circuit to relay 530 which restores, opens the circuit to RLM at contacts 534 and opens the circuit to relay 610 (Fig. 6) over lead RS and through contacts 568 at contacts 535. The release magnet RLM restores. Relay 610 restores and recloses the circuit to relay 670 at contacts 612. Relay 670 reoperates to prepare the position to receive another call. All of the equipment in Figs. 5, 6, and 7 is now restored to the condition existing at the time the position was first prepared to receive a call by the operation of the link key LK1.

Relay 260 (Fig. 2) releases in response to the opening of lead 285 at contacts 523 (Fig. 5) and opens the circuits to relays 210 and 250 which

restore. All relays in the trunk circuit have now been restored.

Answering class B calls

In Fig. 1 both a local and a suburban information trunk circuit have been shown, the first being accessible to local subscribers from a local selector, and the second being accessible to suburban subscribers from a suburban selector. Actually only one type of trunk circuit is required for either use, the only difference being in the interconnection of the trunks with the cordless switchboard. Calls over either of these trunks are classified as class B calls, but it is desirable that the operator be informed whether the call is coming from a local or a suburban subscriber. Only one trunk circuit has been shown in Fig. 3, the differences in connections for the two types of calls being described hereinafter.

The trunk circuit of Fig. 3 is seized by the closure of a loop circuit thereto over leads 350 and 351 from the preceding selector. The release trunk 352 is normally connected to resistance battery in case the preceding selector is the battery searching type. Closure of the loop energizes relay 310 which operates and closes a circuit to relay 330 at contacts 312. Relay 330 operates, connects a source of ring back tone not shown through condenser 353, contacts 331 and 301 to lead 350, connects relay 340 through contacts 332, 323, 345, and 302 to lead BH, closes a circuit to a call waiting lamp not shown through contacts 333 and 303, and over lead 354, and connects ground to lead 352 to mark the trunk 35 busy at contacts 334.

It was previously assumed that the class A trunks were divided into two groups occupying the first and second levels on the banks of the links. It will now be further assumed that there are insufficient class A trunks to fill the second level, the unoccupied contacts being connected to class B trunks, and that the next five levels, i. e. levels 3 through 7, are filled with class B trunks. The class B trunks are further divided into two groups, local and suburban, but this latter grouping need bear no relation to the level grouping thereof. Due to this grouping by levels, six BS leads extend from the call distributor (Fig. 8) to the class B trunk, the particular BS lead which is associated with a trunk being dependent on the level of the link on which that trunk appears. However, the BH lead is not so subdivided but instead is common to all class B trunks. Therefore, if or when there are no marked class B trunks waiting to be answered, the BH lead will be grounded energizing relay 340. Relay 340 operates, connects the lower winding of relay 320 to lead 355 to mark the trunk to the link (Fig. 5) at contacts 343, grounds the BS lead (1 to 6) corresponding to the level of the link on which the trunk appears at contacts 344, and closes its locking circuit independent of the BH lead at contacts 345. Assuming that the call being considered is over a trunk connected to the second level of the links, lead BS1 will have been grounded to energize the upper winding of relay B1 through contacts BG1. Relay B1 operates, closes its holding circuit at contacts B11, grounds lead VBI at contacts B13, and closes a circuit to relay BD (Fig. 9) at contacts B14. Relay BD operates, grounds lead BL at contacts BD1 to light answer lamps, such as BN (Fig. 7) at all operator's positions allocated to receive class B calls and in the supervisor's circuit, grounds lead BPG at contacts BD2 to

operate position grouping relays, such as **BP** (Fig. 6) at all operator's positions allocated to receive class B calls, and opens the circuit to relay **BG** (Fig. 8) and grounds lead **BST** at contacts **BD3**. Relay **BG** restores after a short delay and opens points in the operating circuits to relays **B1** to **B6** at contacts **BG1** to **BG6**, respectively, and removes ground from lead **BH** at contacts **BG7** to prevent marking of class B trunks over which calls are subsequently received. The **BST** lead grounded by contacts **BD3** (Fig. 9) extends through the "B" position distributor (Fig. 11) to the corresponding start lead of an idle operator's position, which will be assumed to be the position illustrated, in which case lead **BST** is extended to lead **BST1** and results in the operation of relay **BR** (Fig. 6). Relay **BR** extends leads **VB1** through **VB6** (corresponding to relays **B1** to **B6**, respectively) to leads **L2** through **L7** (corresponding to the levels on which the trunks associated with relays **B1** to **B6** appear), at contacts **BR9** through **BR4**, thus marking lead **L2** from ground at contacts **B13** over lead **VB1**, transfers leads **BE1** and **BE2** from the corresponding identity lamps **BE1L** and **BE2L** to ground at contacts **BR2** and **BR3**, and closes a circuit to relay **660** at contacts **BR1**. The link is now operated to the second level and rotated to the marked trunk in the same manner as previously described. In case the class A trunks appear on the first contacts of the second level and the class B trunks appear last, and in case any of these class A trunks have been marked to the link by the operation of a relay such as **220** (Fig. 2) the link will pass over such trunks since the **E** leads corresponding thereto, which are encountered by wiper **W4** during the rotary trunk hunting movement of the link, will be connected to battery through lamp **AEL** rather than ground at contacts **AR3**. However, the **E** leads corresponding to the class B trunk are grounded at contacts **BR2** and **BR3** thus completing a circuit to relay **510** when the marked class B trunk is encountered by wiper **W3**. When this occurs relay **320** is energized in series with relay **510** through contacts **343**, over lead **355**, through wiper **W3**, contacts **523**, relays **510**, contacts **532**, thence through wiper **W4** to ground at contacts **BR2** or **BR3**. Subsequent operations of the link relays are the same as previously described. When the **W4** wiper is grounded by the operation of relay **520**, and when relay **BR** restores, lamp **BE1L** or **BE2L** is energized over lead **BE1** or **BE2** to identify the type of class B call which has been seized by the link.

Relay **320** operates over the above traced circuit, closes a multiple circuit to relay **330** and removes ground from the **BS** lead at contacts **322**, opens the circuit to relay **340** at contacts **323**, closes its locking circuit at contacts **321**, and closes a circuit to relay **300** at contacts **324**. Relay **300** operates, closes its locking circuit to contacts **333** and opens the circuit to the call waiting lamp not shown over lead **354** at contacts **303**, and disconnects the source of ring back tone from lead **350** at contacts **301**. Relay **340** restores after a brief delay and extends a talking circuit from leads **350** and **351** through contacts **341** and **342**, over leads **356** and **357**, through wipers **W1** and **W2** and over the previously traced circuits to the operator's induction coil **IND** (Fig. 7).

The removal of ground from the start lead, **BS1** in this case, releases relay **B1** which restores causing relay **BD** to restore and relay **BG** to be

reoperated in a manner similar to that previously described for the class A call.

Extending the call to a local subscriber

- 5 Although the equipment shown is intended primarily for information service, occasionally it is necessary for an information operator to extend a connection to a local subscriber. In such an event, the operator operates the dial key **604** (Fig. 6) thereby closing a circuit to relay **600** which operates and closes a circuit from ground, through contacts **601**, over lead **LD**, through contacts **561** (Fig. 5) and **531** to relay **550**, and opens leads **R1** and **R2** at contacts **602** and **603**. Relay **550** operates, locks to ground on the **DH** lead from contacts **631** (Fig. 6) through contacts **562**, **551**, and **531**, and closes a loop circuit to a local line circuit not shown over leads **505** and **506** through contacts **552** and **553**, **565** and **566**, over leads **F1** and **F2**, through contacts **651**, the secondary winding of **IND**, contacts **652**, **635**, and impulsive contacts **791** of dial **790**. The local line circuit has not been shown since it may be any of the well known circuits usually connected to a local subscriber's line. When a selector switch has been associated with leads **505** and **506**, either by a plunger lineswitch, rotary lineswitch, or finder switch, the operator operates the dial **790** to direct the local switch train in the well known manner. Whenever the dial **790** is rotated off normal the contacts **792** are closed, short-circuiting the operator's receiver to avoid clicks therein, and short-circuiting the two lower portions of the secondary winding of **IND** to reduce the impedance thereof so as not to interfere with proper impulsive of the local switches. After the connection to the called local subscriber's line has been established dial key **604** may be restored to release relay **600** which opens the operating circuit to relay **550** at contacts **601**, reconnects leads **R1** and **F1** at contacts **602**, and reconnects leads **R2** and **F2** through impulsive contacts **791** at contacts **603**, thus connecting the calling party's talking circuit across the called line in multiple with the secondary of **IND**. The operator may retire from the connection by restoring the link key **LK1** thus opening the holding circuit to relay **560** through relay **620** at contacts **LK11**. Relay **560** restores, substitutes direct ground for ground over lead **DH** for the locking circuit of relay **550** at contacts **562**; disconnects the local line leads **505** and **506** from the position relays and connects them directly to the talking conductors of the link at contacts **563** through **566**, opens the circuit to relay **540** at contacts **567**, and opens the circuit to relay **610** at contacts **568**. A holding loop is now closed to the local line through impedance coil **507**. Relay **610** restores and opens the circuit to relay **540** over lead **ST** at contacts **611**. Relay **540** restores and removes ground from wiper **W4** at contacts **541** to extinguish the trunk group identity lamp **BE1L** or **BE2L**. Relay **620** restores. The operator may now operate another link key like **LK1** to prepare for the reception of another call in the same manner as described previously.

Recalling the operator or releasing the connection

- 70 The link circuit is arranged so that it is readily adaptable to either release the connection under the control of the calling subscriber or to permit recall of the operator by the calling subscriber. In the first case strap **X** (Fig. 5) is used while in the latter case this strap is

omitted. In either case, when the calling subscriber's loop is opened relay 310 (Fig. 3) is released thereby removing a short circuit from the high resistance upper winding of relay 320 at contacts 311. Relay 320 is now held with its two windings in series over lead 355 and wiper W3 to ground through relay 500. The increased resistance of this circuit permits relay 500 to restore. When relay 500 restores it short-circuits itself at contacts 501 to provide locked in supervision, and closes ground through contacts 511, 527, and 592 to lead SY1 thereby lighting the supervisory lamp SY1L. If strap X is omitted no further operation takes place. If desired, the connection between contacts 501 and 541 may be omitted to permit flashing of lamp SY1L by the calling party. When the operator observes the lighted lamp SY1L she operates key LK1 to connect the position relays with the link, as previously described, to ascertain whether the calling party desires further assistance. If not, key LK1 is restored and momentarily operated to its non-locking position (i. e. to the right) thereby grounding lead RS1.

Relay 530 operates and brings about the release of the link as previously described with the additional function of opening the locking circuit to relay 550 at contacts 531. Relay 550 restores and opens the local line circuit at contacts 552 and 553 to release the local switch train. When the link is released by the operator the circuit to relay 320 is opened at contacts 523 causing relay 320 to restore and open the circuit to relay 330 at contacts 322. Relay 330 restores, opens the locking circuit to relay 300 at contacts 333, and replaces the ground on lead 352 with battery to release the local switch train and mark the trunk idle. Relay 300 restores.

When strap X is used in Fig. 5, opening of the calling subscriber's loop causes the release of relay 530 as just described, but in this case when relay 500 restores a circuit is closed to relay 530 in multiple with lamp SY1L. The operation of relay 530 releases the link and trunk as just described. Lamp SY1L will be energized in multiple with relay 530 until the locking circuit thereto is opened by contacts on VON upon restoration of the link switching mechanism to normal.

When the operator first extended a connection over the local line she may have made an error in dialling, or for some other reason it may be necessary to release the local switch train and again set up a connection thereover without releasing the link. In this event the key 605 is momentarily operated causing relay 630 to operate and open the loop to the local line at contacts 635. The locking circuit to relay 550 will also be opened at contacts 631 but without effect since the operating circuit thereto remains closed at contacts 601. When key 605 is released relay 630 restores and recloses the loop to the local line causing it to be reseized. A connection may again be set up over the local switch train. If the operator desires to release the local switch train and not reseize the local line circuit to establish a second connection, the dial key 604 is first restored causing relay 600 to restore and open the operating circuit to relay 550 at contacts 601, after which key 605 is operated momentarily causing relay 630 to operate and open the locking circuit to relay 550 at contacts 631. Relay 550 then restores and opens the local line circuit at contacts 552 and 553 to release the local switch train.

Extending the call to the supervisor

Instead of extending the call received over the local or suburban trunk circuit over the local switch train, it may at times be necessary to connect the calling party with the supervisor. To do this the operator first notes whether the supervisor's circuit is idle or busy as indicated by the lighting of lamp SBL (Fig. 7). If or when this lamp is extinguished the operator throws key 720 to the left momentarily, thereby grounding the supervisor call lead SC and the supervisor's signal lead SS1. These leads extend over a cable to the link (Fig. 5) where a circuit is closed to relay SR1 from ground over lead SC, through contacts 562', 533, relay SR1, contacts SR13', SR31', SR21', and SR11' to negative battery. Relay SR1 operates, closes its locking circuit to negative battery through its preliminary make contacts SR12' and to ground on lead SR at contacts SR19, extends leads F1 and F2 through contacts SR14 and SR15 to leads S1 and S2, grounds lead SB at contacts SR16 to operate relay 1000 (Fig. 10) and to light the supervisor busy lamps, such as SBL (Fig. 7) at all operator's positions, extends ground over lead SS1 to lead SS at contacts SR18, and opens a point in the operating circuits of relays SR2 and SR3 at contacts SR11'. It might here be noted that relays SR2 and SR3 represent relays corresponding to SR1 but which are associated with links 2 and 3, respectively. Relay 1000 operates and extends ground over lead SS and through contacts 1001 and 1011 to buzzer 1033, which operates as long as key 720 is held operated, to signal the supervisor, closes a circuit to a signal lamp 1034 through contacts 1012 at contacts 1002, and closes ground from contacts 1021 through contacts 1003, over lead SP, through contacts SR17, and over lead SP1 to the supervisor pilot lamp SPL (Fig. 7). When the supervisor answers the call by inserting the plug 1031 of her headset 1030 into jack 1032, a circuit is completed to relay 1020 through the transmitter of the headset 1030. Relay 1020 operates and closes a circuit to relay 1010 and opens the circuit to lamp SPL over lead SP at contacts 1021. Relay 1010 operates and opens the circuits to buzzer 1033 and lamp 1034 at contacts 1011 and 1012, respectively. Either the information operator or the calling party may now converse with the supervisor. If desired, the information operator may retire from the connection by restoring the link key LK1, relay SR1 remaining locked to ground on lead SR. In this case the supervisor's talking conductors S1 and S2 will be connected directly to the link talking conductors at contacts 563 and 564 through contacts SR14 and SR15 when relay 550 restores. When the supervisor subsequently withdraws plug 1031 from jack 1032 relay 1020 restores, releases relay 1010 and recloses a circuit to lamp SPL over lead SP at contacts 1021. The information operator may then release the supervisor's circuit by momentarily operating key 720 to the right, thus removing ground from lead SR and opening the locking circuit to relay SR1 (Fig. 5) which restores and removes ground from the SB lead to release relay 1000 and to extinguish the busy lamps, such as SBL. If the calling party has also disconnected, this fact will be indicated by the lighting of lamp SY1 and the operator may then release both the link and the supervisor's circuit by operating the corresponding link key LK1 to the right momentarily instead of operating key 720 to the right. Relay 530 is then operated and

brings about the release of the link as previously described with the additional function of opening the locking circuit to relay SR1 at contacts 538. When strap X is used in Fig. 5 both the link and the supervisor's circuit will be automatically released when the calling party disconnects, as should be apparent from the preceding description.

It may here be noted that the operator may operate relay SR1 when the link is at normal, in which case relay SR1 grounds lead LB1 to light the link busy lamp LB1L at contacts SR12, grounds lead RS at contacts SR13 to operate relay 610 and thereby cause the release of 670 to mark the position busy to the position distributors, and opens a point in the circuit to relay 540 at contacts SR11 to prevent the subsequent operation of relay 610 from operating the link switching mechanism. The supervisor's circuit operates as just described and is released in the same manner.

Answering class C calls

The toll information trunk circuit shown in Fig. 4 serves a manual toll board located near the cordless switchboard. The three conductors 450, 451, and 452 terminates in ring, tip, and sleeve terminals of jacks on the manual toll board. When an operator at the manual board calls the information operator by inserting a plug into one of these jacks, battery is connected to the sleeve of the jack thus completing a circuit to relay 400 over lead 452. Relay 400 operates, grounds lead 453 through contacts 413 at contacts 402 to light a call waiting lamp not shown, and connects relay 440 to lead CH through contacts 414, 443, and 433 at contacts 403. If or when ground is present on lead CH, relay 440 operates, grounds lead CS at contacts 442 through contacts 432, connects relay 430 to lead 455 at contacts 441 to mark the trunk to the link, and closes its locking circuit independent of lead CH at contacts 443. The class C trunks are divided into groups corresponding to the levels of the links on which they appear just as the other trunks were. Thus there are three leads CS1, CS2, and CS3 corresponding to levels 8, 9, and 0 of the links. Assuming that the call being considered is over a trunk which appears on the eighth level of the links, lead CS1 will be grounded causing relay C1 to operate and ground lead VC1. The subsequent operations of relays CD, CP, and CR, and release of relay CG should be apparent from the foregoing description and therefore need not be described in detail. When relay CR (Fig. 6) operates it extends the ground over lead VC1 to lead L8 to mark the eighth level to the link. It may here be noted that no VC3 lead need be provided since level 0 corresponding thereto is permanently marked in the link. The position relays and link operate as previously described to connect wipers W1, W2, and W3 to leads 456, 457, and 455, respectively. When the trunk is seized by the link, relay 430 is energized in series with relay 500 over lead 455. Relay 430 operates, closes its holding circuit at contacts 431, closes a circuit to relay 410 and removes ground from lead CS at contacts 432, and opens the circuit to relay 440 at contacts 433. Removal of ground from lead CS releases relay C1 (Fig. 8) causing the call distributor to restore to normal in the manner described previously. Relay 410 operates, removes resistance battery from conductors 450 and 451 at contacts 411 and 412 to extend answer supervision to the calling operator, and closes

its locking circuit and removes ground from lead 458 to extinguish the call waiting lamp not shown at contacts 413. Relay 440 restores. The information operator may extend negative battery and ground over leads 456 and 457 by operating her flash key 780 as previously described for a class A call. When this is done relay 420 is operated and reconnects resistance battery to leads 450 and 451 at contacts 421 and 422 to signal the calling operator. When the calling operator removes the plug from the jack connected to this trunk, relay 400 restores and removes a short circuit from the high resistance lower winding of relay 430 at contacts 401. This change in resistance over lead 455 causes relay 500 to restore and light lamp SY1L and also release the link if strap X is used.

Distribution of calls

Now that the operation of the invention has been described in some detail considering only one call at a time in each of the three classes, the manner in which simultaneous or overlapping calls in all three classes are distributed may be described in more general terms, omitting such details as have been covered by the preceding description.

First assume that all positions are allocated to answer all three classes of calls. Now when a number of calls in all three classes are received simultaneously, or within a short time interval determined by the release times of relay AG, BG, and CG in the call distributor, a number of relays, such as A1, will be operated to mark the corresponding vertical marking leads, such as VA1, and the trunks over which the calls are received will be marked to the links by the operation of relays in the trunk circuits, such as relay 440. Relays AD, BD, and CD will be operated and relays AG, BG, and CG will restore to prevent further marking of trunks. The position grouping relays AP, BP, and CP will be operated in all positions and will release relay 680 so as to prevent reoperation of any of the relays AP, BP, or CP, after they are released, until all three have been released. The three start leads AST, BST, and CST will be extended through their corresponding position distributors to the corresponding start leads of one of the positions, say position one. The grounds thus extended over leads AST1, BST1, and CST1 will energize the corresponding relays AR, BR, and CR. All three of these relays will operate momentarily but only one will remain operated. The one which will remain operated is determined by the strapping between terminals T1 to T7. With the strapping indicated relay AR will be the one that remains operated since it locks to negative battery independently of the other two relays at contacts AR7 and opens the operating and locking circuits to the other two relays at contacts AR6. Relay BR receives preference over relay CR in a similar manner when there is no ground on lead AST1. By changing the strapping any desired order of preference may be obtained. For example, if the order of preference desired is BR, AR, CR, strap T1 to T7, T2 to T5, T3 to T6, and T4 to negative battery, or if the order of preference desired is CR, AR, BR, strap T1 to T6, T3 to T7, T4 to T5, and T2 to negative battery. The order of preference need not be the same in different positions. If the first position has the strapping indicated and the second and third positions have the strapping given in the above two examples, respectively, then the first position will answer

a class A call after which the position distributors will be advanced to position 2 where relay BR will be operated causing that position to answer a class B call, after which the position distributors will advance to the third position where relay CR will be operated to cause the third position to answer a class C call. Thus the effect of a graded multiple is obtained even though a straight multiple is employed between the links of all positions. A highly flexible arrangement is thus provided since the strapping of terminals T1 to T7 can readily be varied to meet changing traffic requirements.

Calls in all three classes will continue to be answered in accordance with the preference given the various classes by the positions as they are successively associated with the call distributor by the position distributors. The class of service in which a marked batch of calls will first be exhausted will be that class in which the number of calls included in the batch thereof divided by the number of positions giving preference thereto is the least. Assuming that the batch of class B calls is the first to be exhausted, when the last marked class B trunk is seized the last of the relays B1 to B6 will be released causing relay BD to restore and reoperate relay BG. As soon as relay BG reoperates all of the trunks over which calls have been received during the time that relay BG was restored will be marked to the links and will reoperate the corresponding relays B1 to B6. Relay BD is then reoperated and relay BG released to prevent further marking of class B trunks. During the interval when relay BD is restored the class B position grouping relays, such as BP, will all be released. The circuits to these relays will be open at contacts such as 682 thereby preventing reoperation thereof when relay BD reoperates. Therefore the class B level marking relays, such as BR, are prevented from operating so that only the marked class A and C calls may be answered at all positions. Also with all relays such as BP and 680 restored there will be no ground on the "B" position distributor start lead BDS thus causing this distributor to be inactive. When one of the remaining batches of either class A or C calls is exhausted a new batch thereof will be marked in a similar manner and all positions will then answer calls in the remaining batch. When this remaining batch is exhausted a new batch thereof will be marked, relays such as 680 will be operated in all positions causing relays such as AP, BP, and CP to be reoperated (assuming that there are calls waiting to be answered in all three classes) and the same cycle of operations will be repeated.

Giving preference to particular classes of service

The mode of operation described in the preceding section tends to equalize the waiting time for all calls. In some instances it may be desirable to give preference to a particular class of service so as to provide a shorter average waiting time therefor. This is readily accomplished by strapping the contacts of relays such as 680 which are included in the operating circuits of the position grouping relays corresponding to the class of service which is to have preference. For example, in Fig. 6 a strap is shown connected across contacts 681 whereby relay AP is enabled to operate from ground over lead APG independently of relays BP and CP. The terminals T1 to T7 of the positions thus strapped should be wired so that the corresponding relay AR, BR, or CR

will have first choice. In this case relay AR is given first choice since contacts 681 which are associated with relay AP have been strapped. Now when a batch of class A calls is exhausted and a new batch marked, relays such as AP will be reoperated in all positions thus strapped to permit such positions to answer class A calls in the new batch despite the fact that there may be class B or C calls waiting which were marked earlier. Since the relays such as AR have first choice in the positions thus strapped, class B or C calls will be excluded therefrom as long as any class A calls are waiting to be answered. The other positions will operate as previously described. Several classes of calls may be given preference either in the same or in different positions in like manner.

Blocking a position to particular classes of service

When it is desired that a particular position shall answer one or two, but not all, of the different classes of calls, the class of service keys corresponding to those classes which are to be excluded from the position are operated. For example, if position 1 is to answer class A calls exclusively keys 740 and 750 are operated, thereby opening points in the circuits to lamps BN and CN, to the corresponding position distributor start leads BDS and CDS, to the position grouping relays BP and CP from leads BPG and CPG, and grounding leads BGD1 and CGD1 to mark this position busy to the "B" and "C" position distributors. Relays BP, CP, BR, and CR are thus prevented from operating to exclude class B and C calls from the position. Under this condition of operation the position distributors will not advance over the positions in step with one another as they do when all positions are allowed to answer all classes of calls. For example, if the three position distributors are in step when they leave the last position, the "A" distributor will stop on position 1 but the "B" and "C" distributors will advance to position 2 since position 1 is marked busy thereto. Position 1 will therefore answer a class A call at the same time that position 2 is answering a class B or C call, depending on the preference given therein. Because the position distributors are thus thrown out of step, a position allocated to receive all classes of calls but strapped so as to give preference to a particular class of call will not necessarily receive calls in that particular class exclusively, although that position will receive more calls in that particular class than it would if the preference strapping were omitted. Under heavy traffic conditions only one position will become idle at a time. The preference strapping will then be effective to cause a preferred class to be answered to the exclusion of other classes, as long as calls in the preferred class are waiting, at positions strapped so as to give preference thereto because all three position distributors will start from normal and will reach the position thus strapped at the same time whenever that position becomes free.

Preventing false markings from blocking calls

If one of the start leads to the call distributor is grounded but no marking is extended to the links on the corresponding level thereof, all calls in succeeding levels included in the same class of service would normally be blocked. Such a condition may arise as a result of a false ground on a start lead, such as BST1, or due to a contact failure in a trunk circuit. For example, suppose contacts 343 (Fig. 3) failed to complete a circuit

21

between relay 320 and lead 355 when relay 340 is operated. If this trunk appears on the second level of the links lead BS1 will be grounded causing relay B1 to operate and cause an idle link in a position allocated to answer class B calls to search for a marked trunk in the second level. Since no trunk in that level is marked to the link it will rotate to the eleventh step where the cam springs CAM of the link (Fig. 5) close a circuit to relay 530 through contacts of VON, and connect ground to wiper W4. The contacts encountered by wipers W1 to W3 on the eleventh step are left disconnected, but those encountered by wiper W4 extend over a cable and terminate in contacts such as A12 on relays associated with corresponding levels of the link. Thus lead EA1 is connected to the eleventh contact of the first level, leads EA2 and EB1 to the eleventh contact of the second level, lead EB2 to the eleventh contact of the third level, etc. The ground placed on wiper W4 by the cam springs is thus extended over lead EB1 to the lower winding of relay B1. The relays such as B1 are differentially wound. Relay B1 therefore restores and opens circuits to both of its windings at contacts B11 and B12. The operation of relay 530 in the link causes it to restore as previously described. If there are other class B calls waiting on any of the levels 3 to 7 these calls will now be answered since relay B1 cannot be reoperated until relay BG is reoperated and relay BG will not be reoperated until all marked class B trunks have been seized. If relay B1 was not knocked down all of the idle links searching for class B calls would stop at the second level and rotate to the eleventh position, thus blocking all class B calls appearing on higher levels.

A second type of false marking which might normally block all calls is an open circuit in one of the vertical marking leads, such as might be caused by a failure of contacts A13 to ground lead VA1 when relay A1 is operated. In this case no link would stop on the first level, and consequently the marked trunk appearing thereon could not be seized. Relay A1 would then continue to hold relay AD operated which would in turn hold all of the position grouping relays such as AP operated thereby preventing relays such as 680 from reoperating after all marked trunks, other than those appearing on the first level, had been seized and relays such as BP and CP had consequently been released. At this time there would be no vertical marking extended to the link which first started searching after the last accessible marked trunk had been answered. This link would therefore step to the tenth level, which is permanently marked, and would then rotate to the eleventh step causing the lead connected to the eleventh contact on the tenth level to be grounded. Instead of connecting this lead EC3 to contacts of relay C3, as would be expected from the connection of the corresponding leads on lower levels, it is connected to relay 900 through contacts 834. The link is released by the operation of relay 530 as previously described. The momentary ground placed on lead EC3 by this link causes relay 900 to operate, open points in the circuits to all position grouping relays such as AP over leads APG, BPG, and CPG at contacts 901, 902, and 903, close a locking circuit to its lower winding at contacts 904 through contacts 835 to contacts AG3, and close a circuit to relay AG at contacts 905. Relay AG reoperates and opens the locking circuit to relay 900. Relay 900 restores and recloses the points in the operating

22

circuits to the position grouping relays. During the time that relay 900 was operated the relays such as AP release to reclose the circuits to relays such as 680 which reoperate and prepare circuits to all of the associated position grouping relays. A new batch of class A calls and the previously marked but inaccessible batches of class B and C calls are thus admitted to the switchboard. The calls waiting on the first level are still inaccessible but blocking of other calls has been prevented.

Transfer to alternate call distributor

When either of the two types of failures discussed in the preceding section occur, at least one operator will be aware of the failure since she will receive an acceptance tone but will receive no call over the link which rotates to the eleventh step. The operator may then operate the emergency start key 760 which closes a circuit to relay 690 and grounds lead EMS which extends over a cable to the call distributor and thence through contacts 836, the two windings of relay 820 in multiple, jack points 3D1, 2D2, and 1D2, and fuse FD2 to negative battery. Relays 810 and 820 are differential relays arranged to operate when the circuits thereto are opened, rather than when closed, as fully described in Patent No. 2,152,524. The two windings of relay 820 are now energized in series opposition causing the relay to remain inactive for the moment. Relay 690 operates and closes circuits to relays AR, BR, and CR at contacts 691, 692, and 693, respectively, through contacts AP5, BP5, and CP5, of the relays AP, BP, and CP which are operated. The position relays and an idle link then operate to seize a marked trunk in the previously described manner. The purpose of relay 690 is to bypass the position distributors in the event of a failure therein. This bypass will be effective only if the call distributor is functioning properly. After the link which is operated in response to the operation of key 760 has either seized a trunk (which would occur if a failure had occurred in the position distributors) or rotated to the eleventh step of any level (which would occur in the case of either one of the types of failures described in the preceding section), key 760 is released opening the circuit to relay 820. Relay 820 operates, closes its locking circuit from battery on jack point 3D1, through its two windings in series aiding relation, and through contacts 821 and 822 to ground, and opens the circuit to relay 830 from ground through contacts 802 at contacts 822. Relay 830 restores, opens points in the circuits to relays AG, BG, and CG at contacts 831, 832, and 833, respectively, and closes a circuit to its corresponding relay 800 in the alternate call distributor at contacts 837. Relay 800 operates and opens the locking circuit to relay 820 at contacts 802. Relay 820 restores. The alternate call distributor is identical to the one shown so that it is apparent that the operation of relay 800 will close circuits to the relays therein corresponding to AG, BG, and CG which results in the alternate call distributor taking over the functions of that shown. If key 760 is again operated and released relay 810 in the alternate call distributor will operate to transfer control back to the distributor shown just as described for relay 820. It is to be understood that all leads connected to the call distributor shown are multiplied to the alternate call distributor as indicated. Each distributor is

preferably jack mounted to permit ready removal from the switchboard for repair or replacement. Only those jack points involved in the arrangements for preventing transfer in the event that the alternate distributor is out of service are shown. All of the negative battery and ground connections within the first call distributor D1 are obtained from jack points 1D1 and 6D1, excepting that negative battery for relay 820 is obtained from jack point 3D1 through fuse FD2 of the second distributor. Similarly, all of the battery and ground connections within the second call distributor D2 are obtained from jack points 1D2 and 6D2, excepting that negative battery for relay 810 is obtained from jack point 3D2 through fuse FD1 of the first distributor. Thus if fuse FD2 is blown relay 820 cannot be operated to transfer control to the second distributor. When the second call distributor is removed from the switchboard the connection between jack points 1D2 and 2D2 will be opened which also prevents operation of relay 820. The jacks are constructed so that the fifth and sixth jack points will make contact when a switch is removed so as to maintain ground on the fifth jack point to hold relay 830 in switch D1, or 800 in switch D2.

If the first distributor D1 is in use and the corresponding fuse FD1 blows for any reason, relay 800 will restore and close the circuit to relay 800 at contacts 831 causing the second distributor D2 to take over the functions of distributor D1. The operators cannot return control to the first distributor as long as fuse FD1 is open since relay 810 cannot be energized. If the first distributor D1 is removed from its mounting while it is in service jack point 5D1 contacts jack point 5D1 thereby operating relay 800 to place the alternate distributor D2 in service. Relay 810 is disabled by the removal of the connection between jack points 2D1 and 1D1 in this case.

It should be understood that numerous modifications may be incorporated in the invention without departing from the true spirit and scope thereof as defined in the appended claims.

What is claimed is:

1. In a telephone system, a plurality of groups of lines, a marking relay associated with each of said lines operated in response to calls received thereover, a plurality of links having access to said lines, a first means individual to each of said groups of lines operated in response to the operation of marking relays associated with calling ones of said lines in the corresponding group to cause idle ones of said links to seize marked ones of said calling lines, and a second means individual to each of said groups operated in response to the operation of said first means to prevent further operation of said marking relays in response to calls subsequently received over lines included in said corresponding group until all marked lines included therein have been seized by idle links.

2. In a telephone system, a plurality of groups of lines, a marking relay associated with each of said lines operated in response to calls received thereover, a plurality of links having access to said lines, and means individual to each of said groups of lines operated in response to the operation of marking relays associated with calling ones of said lines in the corresponding group to cause idle ones of said links to seize marked ones of said calling lines and to prevent further operation of said marking relays in response to calls subsequently received over lines included in said

corresponding group until all marked lines included therein have been seized by idle links.

3. In a telephone system, a plurality of lines divided into two or more classes, a plurality of operator's positions each allocated to answer calls over lines in one or more of said classes, a plurality of links associated with each of said positions having access to said lines, a marking relay associated with each of said lines operated in response to calls received thereover to mark the associated line to said links, a first means corresponding to each of said classes operated in response to the operation of marking relays associated with lines in the corresponding class to cause idle links in said operator's positions, allocated to answer said corresponding class, to seize the marked lines included therein, and a second means corresponding to each of said classes operated in response to the operation of said first means to prevent further operation of marking relays associated with lines included in said corresponding class until all marked lines included therein are seized by idle links.

4. In a telephone system, a plurality of lines divided into two or more classes, a plurality of operator's positions each allocated to answer calls over lines in one or more of said classes, a plurality of links associated with each of said positions having access to said lines, a marking relay associated with each of said lines operated in response to calls received thereover to mark the associated line to said links, and means corresponding to each of said classes operated in response to the operation of marking relays associated with lines in the corresponding class to cause idle links in operator's positions allocated to answer said corresponding class to seize the marked lines included therein and to prevent further operation of marking relays associated with lines included in said corresponding class until all marked lines included therein are seized by idle links.

5. In a telephone system, a plurality of groups of lines, a plurality of marking relays individually associated with said lines, a plurality of links having access to said lines, means responsive to the operation of the marking relay associated with any one of said lines for causing an idle one of said links to seize said one line, means responsive to the receipt of a call over any one of said lines for closing a point in the operating circuit of the associated marking relay, and means individual to each of said groups of lines operated in response to the operation of said marking relay to open a common point in the operating circuits of the marking relays associated with lines in said corresponding group until all marked lines included therein are seized by idle links, whereby independent batches of calling lines in each of said groups are marked to said links.

6. In a telephone system, a plurality of groups of lines, a plurality of marking relays individually associated with said lines, a plurality of links having access to said lines, means responsive to the receipt of a call over any one of said lines for closing a point in the operating circuit of the associated marking relay, and means individual to each of said groups of lines operated in response to the operation of the marking relay associated with any one of the lines in the corresponding group to cause an idle one of said links to seize said one line and to open a common point in the operating circuits of the marking relays associated with lines in said corresponding

group until all marked lines included therein are seized by idle links, whereby independent batches of calling lines in each of said groups are marked to said links.

7. In a telephone system, a plurality of lines divided into two or more classes, a plurality of operator's positions each allocated to answer calls over lines in one or more of said classes, a plurality of links associated with each of said positions having access to said lines, call distributing means operated in response to the receipt of calls over said lines to mark the calls in independent groups thereof in each of said classes to said links, and means individual to each of said positions operated by said call distributing means to cause idle links associated therewith to seize marked ones of said lines in the classes allocated thereto, said last means operated when a group of marked lines in any one class has been exhausted to prevent seizure of subsequently marked lines in said one class by idle links of the corresponding position until certain of the remaining groups of marked lines in all other classes allocated thereto have been exhausted.

8. In a telephone system, a plurality of lines divided into two or more classes, a plurality of operator's positions each allocated to answer calls over lines in one or more of said classes, call distributing means operated in response to the receipt of calls over said lines to mark the calls in independent groups thereof in each of said classes to said positions, means individual to each of said positions operated to cause marked ones of said lines to be extended to the positions allocated thereto to be answered, said last means operated when a group of marked lines in any one class has been exhausted to prevent extension of subsequently marked lines in said one class to the corresponding position until certain of the remaining groups of marked lines in all other classes allocated thereto have been exhausted.

9. In a telephone system, a plurality of groups of lines, a plurality of operator's positions each allocated to answer calls over lines in one or more of said line groups, call distributing means operated in response to the receipt of calls over said lines to mark the calls in independent groups thereof in each of said line groups to said positions, means operated to cause marked ones of said lines to be extended to the positions allocated thereto to be answered, said last means operated when a group of marked lines in any one line group has been exhausted to prevent extension of subsequently marked lines in said one line group to those positions which are also allocated to answer calls over lines in other line groups until certain of the remaining groups of marked lines in said other line groups have been exhausted.

10. In a telephone system, two groups of lines, a plurality of operator's positions each allocated to answer calls over certain of said lines, one of said positions being allocated to answer calls over lines in either of said line groups, call distributing means operated in response to the receipt of calls over said lines to mark said calls in independent groups thereof in each of said line groups to positions allocated thereto, means at said one position operated to cause marked ones of said lines to be extended thereto to be answered, said last means operated, when a batch of marked lines in one of said line groups has been exhausted, to prevent extension of subsequently marked lines in said one line group to said one position until

the remaining group of marked lines in the other line group has been exhausted.

11. In a telephone system, a plurality of lines divided into two or more classes, a plurality of operator's positions each allocated to answer calls over lines in one or more of said classes, a plurality of links associated with each of said positions having access to said lines, call distributing means operated in response to the receipt of calls over said lines to mark said calls in independent groups thereof in each of said classes to said links, and means operated by said call distributing means causing idle links of a position allocated to answer more than one class of call to seize marked ones of said lines in the classes allocated thereto, said last means operated when a group of marked lines in any one of the classes allocated to said one position have been exhausted to prevent seizure of subsequently marked lines in said one class by idle links of said one position until certain of the remaining groups of marked lines in all other classes allocated thereto have been exhausted.

12. In a telephone system as claimed in claim 25 11, said last means operated when groups of marked lines in all of the classes allocated to said one position have been exhausted to permit seizure of subsequently marked lines in the classes allocated thereto despite remaining groups of marked lines in classes not allocated thereto.

13. In a telephone system as claimed in claim 11, further means operated by said call distributing means causing idle links of another position allocated to answer said one class exclusively to seize marked ones of said lines in said one class, said further means operated when a group of marked lines in said one class has been exhausted to permit seizure of subsequently marked lines in said one class by idle links of said other position despite remaining groups of marked lines in the other classes.

14. In a telephone system, two groups of lines, a plurality of operator's positions, at least one of said operator's positions being allocated to answer 45 calls over lines in either of said line groups, a plurality of links associated with each of said positions having access to those lines which are allocated to the associated position, call distributing means operated in response to the receipt of calls over said lines to mark the calls in independent groups thereof in each of said line groups to the links having access thereto and to cause idle ones of said links to seize marked ones of said lines allocated to the positions associated therewith, and means operated in response to the exhaustion of a group of marked lines in one of said line groups to prevent idle links of said one position from seizing subsequently marked lines in said one line group until the remaining 55 group of marked lines in the other line group has been exhausted.

15. In a telephone system, a plurality of groups of lines, a plurality of links having access to said lines, a plurality of leads each corresponding to one of said lines for marking a line to said links, a plurality of leads each corresponding to a group of said lines for marking a group to said links, means operated in response to calls received over said lines to mark the corresponding individual 65 marking leads and to prepare circuits for marking the corresponding group marking leads, said group marking leads being scanned in a predetermined order by said links in searching for a calling line, and means causing said prepared circuits to be completed in a different desired order

when calls over lines in several groups are simultaneously waiting to be answered and causing idle ones of said links to be successively operated to seize the marked lines in a corresponding desired order.

16. In a telephone system, a plurality of groups of lines, a link having access to said lines, a plurality of leads each corresponding to one of said lines for marking a line to said link, a plurality of leads each corresponding to a group of said lines for marking a group to said link, means operated in response to calls received over said lines to mark the corresponding individual marking leads and to prepare circuits for marking the corresponding group marking leads, said group marking leads being scanned in a predetermined order by said link in searching for a calling line, and means causing said prepared circuits to be completed in a different desired order when calls over lines in several groups are simultaneously waiting to be answered and causing said link to be successively operated to seize the marked lines in a corresponding desired order as said link becomes idle intermittently.

17. A telephone system as claimed in claim 15 in which said last means includes a group of relays each corresponding to one of said group marking leads, said relays being interconnected so as to provide a predetermined order of preference in operation thereof when two or more operating circuits are simultaneously completed thereto.

18. A telephone system as claimed in claim 16 in which said last means includes a group of relays each corresponding to one of said group marking leads, said relays being interconnected so as to provide a predetermined order of preference in operation thereof when two or more operating circuits are simultaneously completed thereto.

19. In a telephone system, a plurality of groups of lines, a plurality of links having access to said lines, a call distributor operated in response to calls received over said lines to mark calling ones thereof to idle ones of said links group by group for selection in a predetermined order, whereby said idle links are operated to seize each marked calling line in a given group prior to seizure of the marked calling lines in another group, and means in said distributor operated in response to an idle link attempting to find a marked calling line in a group but failing to do so for removing the corresponding group marking, whereby false markings are rendered ineffective to block calls over lines in other groups.

20. In a telephone system, a plurality of groups of lines, a plurality of links having access to said lines, a call distributor operated in response to calls received over said lines to mark a group of calling ones thereof to idle ones of said links line group by line group for selection in a predetermined order, whereby idle ones of said links are operated to seize each marked calling line in a given line group prior to seizure of the marked calling lines in another line group, and means operated in response to an idle link attempting to find a marked calling line in the last choice line group but failing to do so to cause said distributor to mark a new group of calling ones of said lines to idle ones of said links, whereby faulty markings are rendered ineffective to block calls over lines in earlier choice line groups.

21. In a telephone system, a plurality of groups of lines, a plurality of links having access thereto, a plurality of leads each corresponding to one of

said lines for marking calling ones thereof to said links, a plurality of leads each corresponding to one of said groups for marking the groups including calling lines to said links, means operated in response to the receipt of a call over one of said lines to mark the corresponding ones of said leads and to cause an idle one of said links to be operated to seize the marked calling line, and means in said links operated in response to the seizure

10 of a line to mark the corresponding one of said group leads to identify the group to an operator.

22. In a telephone system, a plurality of groups of lines, at least one of said groups being divided into subgroups, a plurality of links having access to said lines, a plurality of leads each corresponding to one of said lines for marking calling ones thereof to said links, a plurality of leads each corresponding to one of said groups or subgroups for marking the groups or sub-groups including calling lines to said links, means operated in response to the receipt of a call over one of said lines to mark the corresponding ones of said leads and to cause an idle one of said links to be operated to seize the marked calling line, and means in said links operated in response to the seizure

25 of a line to mark the corresponding one of said group or sub-group leads to identify the group or sub-group to an operator.

23. In a telephone system, a plurality of groups of lines, an operator's position including a plurality of links having access to said lines, means operated in response to the receipt of calls over said lines to cause idle ones of said links to be operated to seize the calling lines, means operated in response to the acceptance of a call by an idle one of said links for transmitting an audible signal to an operator at said position, said first means causing the character of said audible signal to vary in accordance with the group in which

40 the calling line being accepted is included.

24. In a telephone system, a plurality of groups of lines, an operator's position including a plurality of links having access to said lines, means individual to each of said groups operated in response to the receipt of calls over lines in the corresponding group to cause idle ones of said links to be operated to seize the calling lines, means operated in response to the acceptance of a call by an idle one of said links for transmitting an audible signal to an operator at said position, the character of said audible signal varying in accordance with which one of said first means is operated at the time said one call is accepted to thereby identify the corresponding group to the operator.

25. In a telephone system, a plurality of lines, an operator's position including a plurality of links having access to said lines, two call distributors one of which is normally inactive, the active one of said distributors being operated in response to the receipt of calls over said lines to cause idle ones of said links to seize the calling lines, and operator controlled means at times operated to render said inactive and active distributors active and inactive, respectively.

26. A telephone system as claimed in claim 25 having a common power supply and wherein power is supplied to said call distributors over individual fuses, and circuit arrangements preventing transfer of control by said means when the fuse of the inactive distributor is open.

27. A telephone system as claimed in claim 25 wherein said call distributors are individually jack mounted, and circuit arrangements preventing

transfer of control by said means when the inactive distributor is removed from its jack.

28. A telephone system as claimed in claim 25 having a common power supply and wherein power is supplied to said call distributors over individual fuses and wherein said call distributors are individually jack mounted, and means operated in response to the removal of the active distributor from its jack or to the blowing of its fuse for rendering the inactive one of said distributors active.

29. In a telephone system, a plurality of operator's positions, a plurality of trunk groups terminating in said operator's positions, a marking means for each trunk group in each operator's position, means responsive to a trunk call in one of said trunk groups for operating the corresponding marking means at an idle one of said operator's positions to allocate said one call to the operator thereat to be answered, and circuit arrangements providing a predetermined order of preference in the operation of said marking means at each position in response to the simultaneous allocation thereto of trunk calls in several of said trunk groups by said first means.

30. In a telephone system as claimed in claim 29, manual cross connecting means for at times completing new circuit connections and thereby changing said predetermined order of preference in the operation of said marking means at each position.

31. In a telephone system, a plurality of operator's positions, a plurality of groups of trunk lines terminating in said operator's positions, a marking means for each group of trunk lines in each operator's position, means responsive to calls over said trunk lines for marking the calls in independent groups thereof in each of said line groups to said operator's positions and for operating the corresponding marking means at idle ones of said operator's positions to allocate marked calling ones of trunk lines to said idle operator's positions to be answered, and means in each of said operator's positions operated in response to the exhaustion of a group of marked calling lines in one of said line groups for preventing further operation of the corresponding marking means thereat until certain of the remaining groups of marked calling lines in the other line groups have been exhausted.

32. In a telephone system as claimed in claim 31, manual cross connecting means for rendering said last means ineffective to prevent the operation of a desired one of said marking means at one

position, whereby preference in answering is given to the corresponding group of trunk lines at said one position.

33. In a telephone system, a plurality of groups of lines, a plurality of operator's positions each allocated to answer calls over lines in one or more of said groups, a plurality of automatic switches associated with each of said positions having access to said lines, each of said switches having a bank of contacts divided into a plurality of levels, each of said groups of lines being divided into a plurality of sub-groups, each sub-group of lines terminating in a particular level and each level terminating only one sub-group of lines or a plurality of sub-groups from different groups of lines, group marking leads individual to each of said groups for marking all of the lines included therein in said bank, line marking leads individual to each of said lines for marking the corresponding line in said bank, sub-group marking leads individual to each of said levels for marking the corresponding sub-group or sub-groups of lines in said bank, means responsive to a call over any one of said lines for marking the corresponding ones of said group, sub-group, and line marking leads, and for operating said switch to find the level marked in accordance with said sub-group marking, means responsive to said switch finding said marked level for operating said switch over the bank contacts of said level to find and connect with the contacts terminating said calling line in accordance with said group and line markings, means responsive to said switch finding said calling line for marking the corresponding group marking lead, and means at said operator's positions corresponding to each of said groups of lines selectively energized over said group marking leads in accordance with the marking thereof by said switch for identifying the group including said calling line.
